GATE VALVE BODY OR SIMILAR ARTICLE

Marvin H. Grove, 340 Hillside Ave., Piedmont, Calif.

Filed Mar. 7, 1960, Ser. No. 59,633

Term of patent 14 years

(Cl. D78—1)

FIG. 3.

FIG. 2.

FIG. 1.

FIGURE 1 is a front elevational view of a gate valve body or similar article showing my new design;

FIGURE 2 is a side elevational view thereof; and

FIGURE 3 is a top plan view thereof.

The other front of the gate valve body or similar article which is shown is substantially the same in appearance as the front shown, and the side not shown is substantially the same in appearance as the side shown.

I claim:

The ornamental design for a gate valve body or similar article, substantially as shown and described.
